UNITED STATES PATENT OFFICE.

JAMES BENNETT, OF CLEVELAND, OHIO.

BOILER-TUBE AND COMBUSTION-CHAMBER CLEANER.

1,340,144.

Specification of Letters Patent. Patented May 18, 1920.

Application filed February 28, 1916. Serial No. 80,829.

To all whom it may concern:

Be it known that I, JAMES BENNETT, a citizen of the United States, and resident of Cleveland, in the county of Cuyahoga and State of Ohio, have invented certain new and useful Improvements in Boiler-Tube and Combustion-Chamber Cleaners, of which I hereby declare the following to be a full, clear, and exact description, such as will enable others skilled in the art to which it appertains to make and use the same.

The objects of the invention are to provide means for removing the collections of soot and other products of combustion from the flues of a return flue boiler and also by proper manipulation for agitating and driving out all deposits of light ashes and soot collected in the combustion chamber, 20 behind the grate and bridge wall.

This means comprises rotatable steam jet pipes, arranged at different levels in front of the horizontal boiler flues and underneath the vertical draft flues in the air 25 chamber of the smoke box.

By means of these jet tubes, a powerful circulation and current of steam and air combined, is driven through one series of flues, into the combustion chamber and 30 after agitating the light ashes and soot deposited in the combustion chamber by giving a rotary movement thereto under increased draft, drives all products of combustion in a suspended state back to the 35 front of the boiler through other series of flues at a different level, and by means of vertically adjustable jet tubes all products of combustion are driven out of the smoke stack.

40 This is accomplished by means of upper and lower series of jet tubes, which can be adjusted to direct their jets alternately in horizontal and vertical directions.

The improved device is also adapted to 45 furnish dry steam directly to the flues and to agitate the deposited material in the dry state and is therefore efficient in gathering it up and carrying it off in a suspended condition.

50 The jets are arranged in spaced relation to each other in swinging upper and lower series or rows in horizontal tubes in the smoke box which lie back against the smoke box doors when not in use and hence are not

overheated and burned out during the use 55 of the boiler.

The invention includes upper and lower rotatable tubular frames, in which jet nozzles are inserted, and which can be rotated upon horizontal axes, either alternately or 60 simultaneously to provide a current of steam under pressure in any direction desired. That is, the relative angles at which the series of jet nozzles are placed, determines the direction of the current produced 65 through the horizontal flues of the boiler and vertical flues of the artificial draft leading to the smoke stack.

The invention is hereafter more fully described, illustrated in the accompanying 70 drawings, and specifically pointed out in the claims.

In the accompanying drawings Figure 1 is a longitudinal section of a marine boiler showing the artificial draft chamber, the 75 upper and lower frames composed of jet tubes and nozzles, and the action of the device, in producing a rotary agitating movement in the combustion chamber; Fig. 2 is a transverse section through the smoke 80 box and artificial draft chamber showing the vertical and horizontal flues and the arrangement of the swinging frames and jet nozzles in a two furnace boiler; Fig. 3 is a similar view in a three furnace boiler; Fig. 85 4 is a longitudinal section enlarged of one of the jet tubes and nozzles; Fig. 5 is an enlarged section of one of the nozzles; Fig. 6 is an enlarged section of swivel joint permitting rotary motion of each jet frame 90 upon its steam supply tube. Fig. 7 is an enlarged longitudinal section of a portion of one of the jet tubes.

In these views 1 is a tubular boiler of the return flue type; 2 is the furnace; 3 the 95 grate, 4 the bridge wall and 5 the combustion chamber. 6, 6, are the horizontal return flues through which the smoke is conveyed from the combustion chamber 5 to the smoke box 7, which covers the upper 100 half of the front of the boiler. 8 is the artificial or air heating chamber which communicates with the ash pan 9 underneath the grates by means of the air boxes 10, 10.

Through the artificial air chamber pass 105 the vertical smoke flues 11, 11, to the stack 12. Arranged within the smoke box 7 are pivotally mounted at different levels tubu,

lar jet carrying frames 13, 14, respectively. These comprise each a lower horizontal tube T and an upper jet carrying tube T' provided with jet nozzles T², T² spaced to coincide with sheet and air heater above.

The tubes T are connected by means of swivel joints shown enlarged in Fig. 6, with a live steam pipe 15.

The jet nozzles are clearly shown in Figs. 10 4 and 5 to be so shaped as to produce the greatest possible velocity in each jet as it is projected into the adjacent boiler flue. Therefore the mouth is first restricted at t and then belled or curved outward at t', which serves to increase the pressure and speed at the outlet.

These frames 13 and 14 are pivoted transversely in the smoke box, in sleeves S, S, which traverse the air chambers and are 20 rotatable in these sleeves as bearings by means of hand levers L, or any suitable external operating gear.

In Fig. 6 the lever is shown attached to coupling flanges F, F, by means of which 25 the pipe connections are made. One frame 13 is so positioned in the lower part of the smoke box that when rotated it can assume either a vertical position or any angle thereto in an arc of 180°, and when not in use 30 can be laid back against the smoke box door to protect it from the intense heat from the boiler flues. This swinging frame can then be made to inject steam into all the lower flues of the boiler.

35 The other or upper frame 14 is so positioned that it can swing in a similar arc of 180° and the jets from it will inject steam into the flues of the upper half of the boiler or into the vertical flues above; or when not 40 in use this frame can be laid back against the door of the smoke box out of the extreme heat from the boiler tubes.

In employing these jet frames to clear the tubes and combustion chamber they are 45 adjusted in the following manner:

At the start, the frames lie in a substantially vertical position against the door D, as shown in dotted lines in Fig. 1. Next, the upper frame T, is turned vertically toward 50 the vertical flues 11, 11 above, and the lower frame is rotated slowly to inject steam in a rearward direction through the horizontal flues in the lower part of the boiler, and against the rear wall H, of the combustion chamber. The action is to produce a whirling rotary movement of steam and of the products of combustion in the combustion chamber 5, which will loosen the deposit 55 from the bottom and the walls thereof, and agitate all particles of soot or ashes in the combustion chamber 5, and the increased draft caused by injecting steam under pressure will carry away the particles of soot or 60 ashes suspended therein in a forward direc-

tion, through the upper horizontal flues of 65 the boiler into the smoke box 7, at the front of the boiler.

From there the vertically directed draft caused by means of the upper jet frame will carry all particles of soot and ashes 70 upward through the vertical flues 11, 11, into the smoke stack of a marine boiler, or through the chimney of a stationary boiler. The dry soot and ashes also have a scouring 75 effect upon the inner surfaces of the flues like a sand blast, and clear away all fire scale from them.

Afterward the relative positions of the jet frames are then reversed and the upper frame 14 is rotated to a horizontal position 80 so as to inject the steam in a horizontal rearward direction through the upper rows of horizontal flues and the lower frame is rotated to assume a vertical position.

The effect of this action is to provide a 85 strong movement of the draft in the combustion chamber in the reverse direction to the aforesaid movement, as the steam from the upper flues impinges upon the upper part of the back sheet H, it is then projected 90 to the bottom of the chamber to agitate and loosen and carry away the soot and ashes still remaining therein through the flues in the lower part of the boiler in a forward direction into the smoke box, and thence 95 through the vertical flues into the stack by the blast from the lower jet frame 13.

When the flues and combustion chamber are thoroughly cleaned the jet frames are returned to their first position lying against 100 the door.

By producing a perfectly clean combustion chamber a great saving in fuel and greatly increased boiler efficiency is attained, and a great increase in efficiency over that obtained by merely cleaning out the flues 105 alone.

In marine boilers the device is particularly desirable because of the non-accessibility of the combustion chamber for 110 cleaning.

In the proper method of operating the device no moist steam can ever enter the horizontal flues since the jets are first turned upward until the moisture of condensation 115 is driven out of the frames and only dry steam is permitted to enter the combustion chamber and horizontal flues.

This feature alone is of the utmost importance therefore the jet frames are preferably independently adjustable for vertical and horizontal positions which can be alternately assumed at the will of operator.

The preferable form of swinging or rotatable joint is shown in Fig. 6, where K is 125 packing box on one portion and K' is a packing gland having a cap K². The other pipe extremity is provided with a terminal

shoulder K³ and is slidable and revoluble in the packing box K.

Having described the invention what I claim as new and desire to secure by Letters Patent is:

1. A device for cleaning the soot and ashes from the combustion chamber and tubes of a horizontal boiler having a smoke box, and for driving them vertically into the smoke stack, comprising, upper and lower rows of swinging steam jets, said rows arranged at different elevations in front of said boiler, one row of jets horizontally pivoted to alternately assume vertical and horizontal positions in the upper portion of the smoke box, and the second row, pivoted to alternately assume horizontal and vertical positions in the lower portion of the smoke box, and means for rotating said rows of jets to operate in conjunction to project the steam horizontally through some of the tubes of the boiler against the rear wall of said combustion chamber, thence through the remaining tubes into the smoke box, and thence vertically into the smoke stack.

2. The method of projecting the soot and ashes deposited in the tubes and rear combustion chamber of a horizontal tubular boiler through some tubes into the smoke box; thence through other tubes into the smoke stack, consisting in projecting a horizontally extended row of dry steam jets horizontally through some of the tubes of the boiler against the rear wall of said combustion chamber, to loosen and agitate the soot and light ashes, in the said combustion chamber, and simultaneously therewith projecting other horizontally extended steam jets vertically from in front of the boiler into the smoke stack, to complete a circulation of steam, carrying said soot and ashes in a state of suspension back through the upper flues of the boiler, and vertically into said smoke stack, said horizontally extended rows of jets being arranged respectively adjacent to the top and bottom of said boiler.

3. The method of projecting the soot and ashes deposited in the tubes and rear combustion chamber of a horizontal tubular boiler into the smoke box, and thence into the smoke stack, consisting in; first, projecting a horizontally extended row of dry steam jets horizontally through the lower tubes of the boiler into the combustion chamber, to loosen and agitate the soot and light ashes in said combustion chamber, and simultaneously therewith projecting a hori-

zontally extended row of steam jets vertically from the upper part of the smoke box into the smoke stack, to carry said soot and ashes in a state of suspension back through the upper flues of the boiler, and vertically into said smoke stack, and subsequently reversing the positions of the steam jets to project the steam first horizontally through the upper flues of the boiler and thence downwardly into the combustion chamber to loosen and agitate any remaining soot and ashes in said flues and chamber, and simultaneously to project the material in suspension vertically through the smoke box into the smoke stack.

4. In a marine boiler provided with an inclosed rear combustion chamber and return flues and front smoke outlet, the combination therewith of means providing a complete circulation of steam under pressure through said flues and combustion chamber, comprising, spaced horizontally extended rows of steam jets arranged at different levels in front of said boiler flues, said spaced jets controllable to project one row of said jets through the flues at one level against the rear wall of said chamber, and to project the other row of jets vertically into said smoke outlet in front of said boiler, said series of jets rotatable on horizontal axes to permit reversal of this action.

5. In a device of the character described, the combination with a horizontal boiler rear combustion chamber, breeching, artificial air chamber and vertical flues therein of a rotatable steam pipe provided with spaced jets, horizontally pivoted adjacent to the upper side of the boiler, underneath said vertical flues, and a rotatable steam pipe, provided with spaced jets, horizontally pivoted adjacent to the lower side of the boiler, and means for operating said rotatable steam pipes to project the steam horizontally from one series of jets, through the opposed flues into the combustion chamber and against the rear wall and bottom of said chamber and to project the returning mixture of steam soot and ashes through said vertical flues into the smoke stack.

In testimony whereof I hereunto set my hand this 23rd day of February, 1916.

JAMES BENNETT.
